UNITED STATES PATENT OFFICE.

WILLIAM M. KELLY, OF WESTFIELD, NEW JERSEY, ASSIGNOR TO AMERICAN TYPE FOUNDERS COMPANY, OF JERSEY CITY, NEW JERSEY, A CORPORATION OF NEW JERSEY.

PRINTING PRESS.

Original application filed August 6, 1921, Serial No. 490,290, and in Great Britain July 27, 1922.

Divided and this application filed July 7, 1925. Serial No. 42,086.

The present invention relates to printing presses and particularly to inking mechanism for bed and cylinder presses.

This application is a division of my application Serial No. 490,290, filed August 6, 1921.

One of the objects of this invention is to provide an inking mechanism for presses of this type in which certain of the rolls are driven through transmission mechanism directly connected to one of the members reciprocating the bed and in which certain of the rolls are vibrated by their rotation. The advantageous result obtained by this method of driving the inking rolls is that the position of the rolls is always timed to the cycle of operation of the press, so that if these rolls are raised and thereafter lowered to operative position, their lines of contact with the cooperating rolls will be unaltered.

A further object in connection with the inking rolls is to provide an adjustable vibrating means so that the throw or extent of vibration of the rolls may be varied independently, one roll vibrating more than another and thus giving a better and more uniform distribution or "cutting up" of the ink.

A still further object is to provide means for raising the distributing rolls from the form rolls without disturbing the operating connections of the former and to provide convenient means for holding the rolls in either their operative or raised positions.

Referring to the accompanying drawings: Figure 1 is a side elevation of a fragment of the press fully shown in my application referred to above, this view showing only those parts of the press directly associated with the inking mechanism;

Figure 2 is a side elevation of the opposite side of the press, this view also omitting all elements of the press except those necessary to illustrate the inking mechanism;

Figure 3 is a vertical longitudinal section through the press, showing more particularly the inking rolls and the train of gearing for operating the rolls;

Figure 4 is a diagrammatic view illus-

trating the mechanism for reciprocating the bed and actuating the inking rolls;

Figure 5 is a side elevation of the pivoted inking roll frame; and

Figure 6 is a partial plan view, parts 55 being in section, illustrating means for vibrating the ink rolls.

The inking mechanism may be of any suitable form, but according to the present invention, some of the rolls, preferably the 60 vibrator rolls, are driven from the bed reciprocating mechanism. As shown in Figures 1 and 2, the form rolls 92 are carried in suitable adjustable bearings 93. The upper rolls 96 and 98 and the vibrator rolls 65 97 are carried in bearings on a pivoted frame 94 pivoted on a shaft 95. A roll 96 rests on the vibrator rolls 97, and a roll 98 rests on one of the vibrator rolls 97 and a large pipe roll 99, this latter roll being concentric with the pivots of the frame 94. Ink is transferred from the fountain roll 100 to the roll 99 by a ductor roll 101, the fountain 102 being of any suitable construction. The side members of the frame 94 75 at their free ends rest on lugs 103 carried by the cylinder housings of the press, and the frame is locked down against elevating movement by the arms 104 carried by a shaft 105 secured to the cylinder housings. 80

One end of this shaft is provided with a knob 106 at one side of the press so that when this knob is rotated both arms 104 will be swung upwardly. Thereafter by depressing the handle 107, the ink roll frame 85 94 may be elevated to the position 108 indicated by the dotted lines in Figures 1 and 2. To hold the ink frame in this elevated position, the arms 104 may be swung under the tip ends of the side members of the 90 frame, assuming the position indicated by the dotted lines 109.

The fountain roll 100 is intermittently operated by means of the ratchet mechanism 110, the latter being operated from a 95 cam (not shown) through connections including link 111 and lever 112.

The mechanism for oscillating the ductor roll 101 comprises a cam 118 disposed between the segmental gear 49 and the side 100

frame 36, this cam acting on a bell crank lever 119 (see Figure 2) connected by link 120 to the arm 121. A spring 122 holds the bell crank in contact with its cam 118.

6 Referring to Figures 3 and 4, the train of gears for rotating the vibrator rolls 97 is driven from the gear 54 on shaft 53, said gear meshing with the bed rack and thereby actuating the bed. Gear 54 also drives a 10 gear on shaft 124, and gear 125 on this shaft meshes with gear 126 which in turn drives gear 127, then gear 128, the train being completed by the gears 129, 130, 131 and 132. (See Figure 4). In this manner the vibrator rolls 97 are positively connected with the bed driving gear and their rotations are therefore timed with the reciprocation of the bed, so that even if the vibrator rolls are elevated and then moved back to operative 20 position, they will return to exactly the same lines of contact with the other rolls.

According to the present invention, the vibrator rolls are vibrated by their rotation. Thus referring to Figure 6, at one of their 25 ends, each of the rolls 97 has a threaded shaft 135 operating in a nut 136. As shown in Figure 6, these nuts are secured to the frame 94 by the bolts 137 and by loosening these bolts the nuts 136 may be permitted an 30 axial movement, thus reducing the extent of vibration of the rolls 97. Hence the vibration of the rolls may be adjusted and independently, that is to say, the extent of vibration of one roll may be different from 35 that of the other, thus distributing and cutting up the ink better. This adjustment of the extent of vibration is of great utility in connection with the employment of differently colored inks. Furthermore, the particular form of vibrating means used assures 40 the return of the rolls to their exact former positions after the frame 94 has been raised. Hence the vibrating means in conjunction with the means for rotating the rolls provides 45 for the rotation and vibration of the rolls in exact timed relation with the cycle of movements of the press.

Having thus described the invention, what is claimed as new and desired to be secured 50 by Letters Patent is:

1. In a printing press, in combination, a reciprocating bed, means to actuate the bed including a shaft, and a gear on the shaft engaging the bed; inking mechanism comprising a plurality of lower rolls, upper rolls, a pivoted frame carrying said upper rolls, means to rotate some of said upper rolls from said shaft and means to vibrate some of said upper rolls actuated by said 55 rotation, including nuts axially slidable in said pivoted frame and threads on the roll shafts cooperating with said nuts.

2. In a printing press, in combination, a reciprocating bed, means to actuate the bed 60 including a shaft, and a gear on the shaft

engaging the bed; inking mechanism comprising a plurality of lower rolls, upper rolls, a pivoted frame carrying said upper rolls, means to rotate some of said upper rolls from said shaft and means to vibrate said 70 upper rolls actuated by their rotation, including nuts and threads on the roll shafts cooperating with said nuts, said nuts being mounted for adjustable axial movement to regulate the extent of vibration of said upper rolls.

3. In a printing press, vibrating ink rolls, and means to vibrate said rolls including threads thereon and nuts cooperating therewith, said nuts being mounted for adjustable lost motion in an axial direction to vary the extent of vibration of said rolls.

4. In a printing press, vibrating ink rolls, and means to vibrate said rolls including threads thereon and nuts cooperating therewith, said nuts being mounted for independently adjustable lost motion in an axial direction to vary the extent of vibration of said rolls.

5. In a printing press having a pivoted frame carrying inking rolls; means for engaging the top of said frame to lock said frame in its normal position, said means also being adjustable to engage the under side of said frame to hold the frame in 95 raised position.

6. In a printing press having a main frame and a pivoted frame carrying inking rolls; means pivoted on said main frame and operable from one side of the press about 100 its pivot to lock the frame in its normal position or hold it in raised position.

7. In a printing press having a pivoted frame carrying inking rolls; means operable from one side of the press to lock the 105 frame in its normal position or hold it in raised position, said means engaging opposite lateral sides of said frame.

8. In a printing press having a pivoted frame carrying inking rolls, a shaft disposed parallel to the rolls and having an arm at each end thereof adapted to engage the frame and hold it in normal position, said shaft being rotatable from one side of the press to carry said arms to a position to 115 hold the frame raised.

9. In a printing press, in combination, a reciprocating bed, means to actuate the bed including a shaft and a gear on the shaft engaging the bed; inking mechanism including a plurality of lower rolls, upper rolls, a pivoted frame carrying said upper rolls, means to drive said upper rolls from said shaft including a gear coaxial with the pivots of said frame, and means for engaging the top of said frame to hold it in normal position, said means being movable to engage the under side of said frame to support it in its raised position.

10. In a printing press, in combination, a 130

reciprocating bed, means to actuate the bed including a shaft and a gear on the shaft engaging the bed; inking mechanism including a plurality of lower rolls, upper 5 rolls, a pivoted frame carrying said upper rolls, means to rotate said upper rolls from said shaft including a gear coaxial with said frame, means to vibrate some of said upper rolls by their rotation, and means 10 journaled in said pivoted frame for adjusting the extent of vibration.

11. In a printing press, inking mechanism including a plurality of form rolls, distributing rolls coacting therewith, a pivoted 15 frame carrying said distributing rolls and means to rotate and vibrate said distributing rolls including a gear coaxial with said frame, and means mounted entirely on said pivoted frame for rendering the vibrating

means ineffective for a part of the rotation 20 of the rolls.

12. In a printing press, in combination, a supporting frame, a vibrating ink roll, means coaxial therewith to vibrate said roll, 25 said means being mounted for sliding movement in said frame axially with respect to said roll.

13. In a printing press, in combination, a supporting frame, a vibrating ink roll, 30 means coaxial therewith to vibrate said roll, said means being mounted for axial and rotary movement in said frame, and means for adjusting the limits of said axial movement to vary the extent of vibration of said roll.

In testimony whereof I hereunto affix my signature.

WILLIAM M. KELLY.
